UNITED STATES PATENT OFFICE.

CARL LAWRENCE MATTISON, OF BELOIT, WISCONSIN, ASSIGNOR TO C. MATTISON
MACHINE WORKS, OF BELOIT, WISCONSIN, A CORPORATION OF WISCONSIN.

BELT-SANDEE.

1,159,060.

Specification of Letters Patent.

Patented Nov. 2, 1915.

Application filed July 5, 1913. Serial No. 777,513.

To all whom it may concern:

Be it known that I, CARL LAWRENCE MATTISON, a citizen of the United States, residing at Beloit, in the county of Rock and State of Wisconsin, have invented certain new and useful Improvements in Belt-Sanders, of which the following is a specification.

This invention relates to sand-papering and polishing machines of the type in which the abrasive is carried upon an endless belt, the belt being pressed against the work by means of a hand block manipulated by the operator.

One of the objects of the invention is to provide a frame constructed of independent sections arranged to be placed at any convenient distance apart in order that pieces of any desired length may be sanded.

Another object of the invention relates to the proper location of the belt.

In previous machines in which the lower run of the belt is manipulated into contact with the work, the upper run has been so located that the operator's head was liable to come into contact therewith. I have provided means for supporting the upper run of the belt at such a height from the floor that it shall be out of the way of the operator.

A further object of the invention is to improve the construction of the tables used in this class of machine.

In the accompanying drawings, Figure 1 is a front elevation of a belt sander embodying the features of my invention. Fig. 2 is a top plan view of the machine. Fig. 3 is an end elevation of the table. Fig. 4 is a view of a hand block that may be used with the machine.

In machines of this class it is desirable that the machine shall be expandible to handle material of any length. I, therefore, construct the frame of the machine of two pedestals 1 and 2 which are structurally independent one of the other, each pedestal having a base adapted to rest firmly upon and be secured to the floor. These pedestals may be placed upon the floor at any distance apart in order that work of any length may be placed between them. The pedestals are provided with bearings for shafts 3 and 4, respectively. On the shaft 3 are tight and loose pulleys 5 and 6, respectively. Fixed upon the shafts 3 and 4 are pulleys 7 and 8,

respectively. Each of the pedestals also has an upwardly extending arm or bracket 9 and 10, respectively. The bracket 9 carries an idler pulley 11. A lever 12 of the first order is pivoted to the bracket 10. Upon the inner end of the lever 12 is journaled an idler pulley 13, and at the opposite end portion of the lever 12 is an adjustable weight 14.

An endless belt 15 extends around the pulleys 7, 8, 11 and 13. The pulleys 7 and 8 are located at such a height from the floor that the operator can press the lower run of the belt downwardly against the work with his arm inclined downwardly at a comfortable and convenient angle, and without assuming an unnatural position. The pulleys 11 and 13 are supported at such a height that the operator's head is not likely to come into accidental contact with the upper run of the belt. All parts of the belt being above the work, there are no obstructions to interfere with lowering the table as much as may be necessary to take work of unusual thickness. The sand paper or other abrasive material is located upon the outer side of the belt, that is to say, the side opposite to that which is in contact with the pulley, the abrasive being thus able to clear itself of dust to a considerable degree as it passes around the pulleys.

The work is supported upon a table which is structurally independent of the pedestals 1 and 2. The supporting frame of the table comprises two end members 16 and 17 and the connecting member 18. The table top 19 is provided with rollers 20 and 21 which are adapted to run upon two rails 22 and 23, each of said rails being secured to a slide 24 (Fig. 3). The slides 24 are mounted for vertical movement upon dove-tail guides 25 on the outer side of the end members 16 and 17. To each slide is fixed a rack bar 26 that meshes with a pinion 27 fixed upon the ends of a shaft 28, said shaft being suitably journaled in bearings in the end members 16 and 17 and the connecting member 18. The shaft 28 is arranged to be rotated by means of a hand wheel 29 fixed to a worm 30 which meshes with a worm wheel 31 fast on the shaft 28.

In use, the table is adjusted by means of the hand wheel 29 to the desired height, and the work is laid upon the table top 19. Power being communicated to the drive pul-

ley 5, the belt 15 is rapidly moved over the work with the sanded side toward the work. By means of a hand block 32 of any suitable form, the operator depresses the belt 15 into contact with the work, moving the hand block longitudinally of the belt and shifting the table top transversely of the belt as may be necessary to bring the belt into contact with all portions of the work.

10. The pulleys 7 and 8 are supported relatively far apart. The portion of the belt extending between said pulleys is thus comparatively long and therefore flexible and may be readily depressed into contact with the work and also flexed transversely into contact with curved surfaces. Being structurally independent of the remainder of the machine framework, the table is not affected by vibrations or stresses set up in the pedestals 1 and 2, and may be constructed as substantially as may seem desirable. Thus the parts of the table do not get out of alignment, and the table top rolls freely back and forth upon the rails 22 and 23.

I claim as my invention:

In a belt sander, the combination of two pedestals which are structurally independent of each other, a pair of sand-belt-carrying pulleys on each of said pedestals, a sand belt running over all four of said pulleys, the two upper pulleys being arranged to maintain the upper run of said sand belt in an elevated position so as to be out of the way of the operator and one of said upper pulleys being movable to take up slack in the belt, a drive pulley rigidly connected to one of the lower belt-carrying pulleys, and a work-support which is structurally independent of said pedestals, said work-support being positioned wholly beneath both runs of said belt.

In witness whereof, I hereby affix my signature in the presence of two witnesses.

CARL LAWRENCE MATTISON,
